(57) **CLAIM**

The ornamental design for a synchronous learning device, as shown and described.

DESCRIPTION

FIG. 1 is the perspective view of a synchronous learning device showing my new design;
FIG. 2 is the front view thereof;
FIG. 3 is the rear view thereof;
FIG. 4 is the left side view thereof;
FIG. 5 is the right side view thereof;
FIG. 6 is the top view thereof;
FIG. 7 is the bottom view thereof; and,
FIG. 8 is a perspective view thereof showing the synchronous learning device in use, the broken lines are shown to illustrate environment only and form no part of the claimed design.
